UNITED STATES PATENT OFFICE.

JOSEPH F. BREZINSKI, OF CHICAGO, ILLINOIS, ASSIGNOR OF ONE-HALF TO ANDREW OWCZARZAK, OF CHICAGO, ILLINOIS.

DAVENPORT-BED.

1,087,718.

Specification of Letters Patent.

Patented Feb. 17, 1914.

Application filed April 9, 1913. Serial No. 759,957.

To all whom it may concern:

Be it known that I, JOSEPH F. BREZINSKI, a citizen of the United States, and a resident of the city of Chicago, county 5 of Cook, and State of Illinois, have invented certain new and useful Improvements in Davenport-Beds, of which the following is a specification.

My invention relates to improvements in 10 davenport-beds and has for its object the provision of an improved construction of this character which may be readily converted into either a davenport or a bed.

The invention consists in the combinations 15 and arrangements of parts hereinafter described and claimed.

The invention will be best understood by reference to the accompanying drawings forming a part of this specification, and 20 in which—

Figure 1 is a side view of a davenport-bed embodying my invention and shown with one of the end members thereof removed and the parts positioned for use as 25 a davenport, Fig. 2, a similar view, but showing the parts in position for use as a bed, Fig. 3, a section taken on line $x-x$ of Fig. 2, Fig. 4, a front view of the construction, Fig. 5, a section taken on line $y-y$ of Fig. 4, and Fig. 6, a detail section 30 taken through one of the end members showing the pivotal mounting employed for supporting the back member of the davenport.

The preferred form of construction as 35 illustrated in the drawings comprises suitable end members 1 which may be of any desired shape or construction. These end members are detachably connected together by means of a head rail 2 which is detachably connected at each end with the corresponding end member by means of a bifurcated bracket 3 engaging a bolt 4 and a dowel pin 5 as shown. The end members are also detachably connected by a supporting rail 6 which is provided at each end with a headed stud 7 engaging suitable key hole sockets in the end members just as the side rail of an ordinary bed is secured to the head and foot thereof. Each of the end 50 members 1 is provided at its lower central portion with an inwardly extending trunnion 8 which fits in a socket in the lower portion of the corresponding end of a back member 9 which is adapted to constitute the

back of the davenport and a portion of the 55 bed. Member 9 is shaped at its upper side 10 to fit head rail 2 and is provided on one face with upholstering 11 and on its other face with a mattress or other suitable bed material 12. A bed member 13 is hinged to 60 the upper rear portion of back member 9 to hang at the rear thereof, said bed member being provided on one face with a mattress 13' or other suitable bed material and at each side with a supporting leg 14 adapted 65 to support the free edge thereof when the parts are utilized as a bed as indicated in Fig. 2. At each end back member 9 is provided with a downwardly and forwardly 70 extending bracket 15 and a seat member 16 is pivotally mounted between said brackets, the upper face of said seat member being provided with suitable upholstering 16' and the outer end of said seat member being mounted on swinging arms 17 pivoted there 75 to and to the corresponding end members, said arms being so positioned as to cause the outer free edge of seat member 16 to be lifted and placed on supporting rail 6 upon forward movement of said seat member. 80 Suitable straps 18 and 19 are arranged at the upper and free edge respectively of back member 9 and bed member 13 to facilitate manipulations thereof.

In use all that is necessary to convert the 85 construction into a bed is to take hold of the strap 18 and draw the upper portion of the back member 9 forwardly. Back member 9 will swing upon its trunnions 8 until it rests upon top rail 6 as shown in Fig. 2. 90 This movement causes rearward movement of seat member 16 into the position shown in Fig. 2, and bed member 13 may then be moved into the position shown in Fig. 2 to complete the bed, supporting legs 14 being 95 utilized to support the free edge thereof. When it is desired to convert the construction into a davenport or couch, legs 14 are folded against the sides of bed member 13 and said member folded on to the top of 100 back member 9. Then back member 9 is swung upward to the position shown in Fig. 1 and seat member 16 will automatically assume its proper position. This construction is very simple comprising but few parts 105 and is readily converted by a simple and easily performed manipulation.

While I have illustrated and described the

preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

10 Having described my invention what I claim as new and desire to secure by Letters Patent is:

15 1. A construction of the class described comprising end members; a back member pivoted on said end members and having the rear thereof arranged to serve as a bed member; a seat member mounted upon swinging arms and pivotally connected with the lower end of said back member; and a bed member 20 pivotally connected with the upper portion of said back member and having the inner face thereof arranged to serve as a bed member, substantially as described.

25 2. A construction of the class described comprising end members; a back member pivoted on said end members and having the rear thereof arranged to serve as a bed member; a seat member mounted upon swinging arms and pivotally connected with the lower 30 end of said back member; a bed member pivotally connected with the upper portion of said back member and having the inner face thereof arranged to serve as a bed member; and supporting legs on said bed member, substantially as described.

35 3. A construction of the class described comprising end members; a back member pivoted at its lower end on said end members and having the rear thereof arranged 40 to serve as a bed member; a seat member mounted upon swinging arms and pivotally connected with the lower end of said back member; and a bed member pivotally connected with the upper portion of said back 45 member and having the inner face thereof arranged to serve as a bed member, substantially as described.

50 4. A construction of the class described comprising end members; a back member pivoted at its lower end on said end members and having the rear thereof arranged 55 to serve as a bed member; a seat member mounted upon swinging arms and pivotally connected with the lower end of said back member; a bed member pivotally connected with the upper portion of said back member and having the inner face thereof arranged 60 to serve as a bed member; and supporting

legs on said bed member, substantially as described.

60 5. A construction of the class described comprising suitable end members; a back member pivoted on said end members; a seat member pivotally connected with the lower end of said back member; a bed member pivotally connected with the upper portion of said back member; a supporting rail connecting said end members and arranged to support the free edge of said seat member; and arms pivoted to said seat member and said end members and adapted to lift the free edge of said seat member onto said rail upon forward movement of said seat member, substantially as described.

65 75 6. A construction of the class described comprising suitable end members; a head rail detachably connected with said end members; a trunnion on the inner side of each of said end members; a back member provided with a socket at the lower portion 80 of each of its ends fitting the corresponding trunnion; a bed member pivoted to the upper portion of said back member to hang at the rear thereof; a bracket secured to the lower portion of each end of said back member and extending forwardly therefrom; and a seat member pivoted between said brackets, substantially as described.

85 90 7. A construction of the class described comprising suitable end members; a head rail detachably connected with said end members; a trunnion on the inner side of each of said end members; a back member provided with a socket at the lower portion 95 of each of its ends fitting the corresponding trunnion; a bed member pivoted to the upper portion of said back member to hang at the rear thereof; a bracket secured to the lower portion of each end of said back member and extending forwardly therefrom; a seat member pivoted between said brackets; a supporting rail detachably connecting said 100 end members and arranged to support the free edge of said seat member; and arms pivoted to said seat member and to said end members and adapted to lift the free edge of said seat member onto said rail upon forward movement of said seat member, substantially as described.

105 110 In testimony whereof I have signed my name to this specification in the presence of two subscribing witnesses.

JOSEPH F. BREZINSKI.
